UNITED STATES PATENT OFFICE.

FREDERICK A. NICHOLS, OF BROOKLYN, NEW YORK, ASSIGNOR TO THE COMBINATION ENVELOPE MANUFACTURING COMPANY, OF BOSTON, MASSACHUSETTS, A CORPORATION OF MASSACHUSETTS.

COMBINATION ENVELOP AND MESSAGE BLANK.

No. 830,844.

Specification of Letters Patent.

Patented Sept. 11, 1906.

Application filed January 29, 1906. Serial No. 298,338.

To all whom it may concern:

Be it known that I, FREDERICK A. NICHOLS, a citizen of the United States, residing at Brooklyn, in the county of Kings and State 5 of New York, have invented certain new and useful Improvements in a Combination Envelop and Message-Blank, of which the following is a specification, such as will enable those skilled in the art to which it appertains 10 to make and use the same.

The object of this invention is to provide an improved combination envelop and message or statement blank designed particularly for use by insurance companies in sending 15 out premium notices, by telegraphic companies, and by business men or houses in sending out bills, statements, and announcements of various kinds or classes, a further object being to provide a combination envelop and message or statement blank which may be conveniently folded into the form of an envelop and sealed after the message, bill, or statement has been printed or written 20 thereon, the construction being such that 25 when the blank has been folded into the form of an envelop and sealed the envelop may be opened and the message, bill, or statement at the same time detached by simply pulling off a strip of the envelop, which is separated 30 from the body portion thereof by lines of perforations.

This invention is an improvement on that described and claimed in United States Letters Patent No. 789,957, granted to William 35 H. Bassinger, May 16, 1905, and the invention is fully disclosed in the following specification, of which the accompanying drawings 40 form a part, in which the separate parts of my improvement are designated by suitable reference characters in each of the views, and in which—

Figure 1 is a plan view of the blank which I employ; Fig. 2, a back view of an envelop formed from said blank; and Fig. 3, a transverse section on the line 3-3 of Fig. 2, showing the envelop unsealed, the thickness of the envelop being also exaggerated so as to better show the construction.

In the practice of my invention I provide a 50 blank (shown in Fig. 1) which is cut from any suitable paper or other material and which comprises a body portion *a*, provided at one side edge with a sealing-flap *b*, at the opposite

side edge with a folding member *c*, and at each end with an end flap *d*, and said sealing-flap *b*, folding member *c*, and end flaps *d* are adapted to be folded along corresponding lines *e*, *f*, and *g*. The end flaps *d* are preferably tapered; but the bottom edges thereof adjacent to the body portion of the blank are 60 preferably extended to the bottom edge of said blank, and said body portion of the blank is provided parallel with the folding-line *f* and at a predetermined distance therefrom with a row of perforations *h*, and the 65 folding member *c* is also provided parallel with said folding-line *f* and with the row of perforations *h* and at a predetermined distance therefrom with a similar row of perforations *i*.

The folding member *c* is provided in the form of construction shown with a supplemental folding member *c*², adapted to be folded on a line *j*, and said supplemental folding member *c*² is of less width than the 75 main part of said folding member, the width of the supplemental folding member *c*² being substantially the same as the width of the main folding member *c* between the row of perforations *i* and the folding-lines *j*. 80

In practice, supposing this device to be intended for the use of an insurance company in sending out premium-notices, the said notices are printed or written on either or both sides of the folding member *c* and on the supplemental folding member, if the latter is employed, and if the device is intended for use by a telegraphic company the blank message is printed on the body or main portion of the folding member in the usual manner, and if 85 the device is intended for use by business men, houses, or concerns in sending out announcements of any kind or class the announcement is similarly printed on the body portion of the folding member and on the 90 supplemental part thereof, if the latter be employed. 95

It will be understood, of course, that the address is printed or written on the body portion *a* of the blank in the usual manner, and in folding and sealing the blank into the form of an envelop the folding member *c* is first folded over the body portion *a* and if the supplemental folding member *c*² is employed it is folded downwardly and backwardly, as 100 shown in Fig. 3. The end flaps *b* are then 105

folded over the parts *c* and the sealing-flap *b* is then folded over the end flaps.

The sealing-flap *b* is provided parallel with its free edge with a row of perforations *b*², forming a strip *b*³, which is gummed on the inner side thereof, as shown in Fig. 1, and the lines of perforations *h* and *i* form when the blank is folded as above described a narrow strip *k* at the bottom edge of the envelop to 10 which the strip *b*³ is sealed in the operation of sealing the envelop. In folding the blank into an envelop and sealing it in the manner described the lines of perforations *h*, *i*, and *d*² all register, and this forms a narrow strip *m* 15 at the bottom edge of the envelop which is separated from the body thereof by said rows of perforations, and in opening the envelop all that is necessary is to take hold of one end of the strip *m* and pull it off, and this 20 operation in addition to opening the envelop also detaches the folding member on which the message, statement, or other information is placed, and said message, statement, or other information may be filed away and preserved 25 independent of the envelop. If the body portion of the folding member only is employed, it will be seen that the operation of opening the envelop detaches said folding member and forms therefrom a card which 30 may be conveniently carried in the pocket or in a pocket-book, and this is also true if the part *c*² of the folding member be employed, the separate parts of said folding member being folded along the line *j*.

35 In the construction shown the perforations in the line *h* in the body of the envelop are extended at each end of said line into the end flaps *d*, the object of this being to facilitate the tearing off of the strip *m*, in which operation a portion of the end flaps are also torn off if said end flaps are made as wide as the body portion of the blank, and the object of making the end flaps adjacent to the body portion as wide as said body portion and tapering 40 said flaps is to enable the sealing strip *b*³ to be sealed to the end flaps as well as to the folding member, so as to prevent the pulling out of said end flaps.

It will be understood that when the blank 50 is folded as shown in Fig. 2 it forms a strong and compact envelop of the usual shape which may be securely sealed in the usual manner and the cost of which is comparatively no

greater than the cost of ordinary envelops, and it will also be understood that the envelop may be made of any desired size and of any preferred shape.

Having fully described my invention, what I claim as new, and desire to secure by Letters Patent, is—

1. A combination envelop and message-blank, comprising a body portion provided at one side edge with a sealing-flap, at the opposite side edge with a folding side member, and at the opposite ends with folding end flaps, the body portion being provided parallel with the folding side member and adjacent thereto with a row of perforations, and the folding side member being provided parallel with the body portion and adjacent thereto with a corresponding row of perforations, and the sealing-flap being also provided adjacent to its free edge with a row of perforations for forming a narrow strip which is gummed on its inner side, the rows of perforations in the body portion, folding side member and sealing-flap being adapted to register when the envelop is sealed, substantially as shown and described.

2. A combination envelop and message-blank, comprising a body portion, a sealing-flap at one side edge of the body portion, a folding side member at the opposite side edge of the top portion, and folding end flaps, said body portion being provided adjacent to the 85 folding-line of the side member and parallel therewith with a row of perforations which are extended into the end flaps, and said side member being provided adjacent to the folding-line thereof and parallel therewith with a 90 row of perforations, and the sealing-flap being provided adjacent to its free edge with a row of perforations forming a narrow strip which is gummed on its inner side, the rows of perforations in the body portion, folding 95 side member and sealing-flap being adapted to register when the envelop is sealed, substantially as shown and described.

In testimony that I claim the foregoing as my invention I have signed my name, in 100 presence of the subscribing witnesses, this 27th day of January, 1906.

FREDERICK A. NICHOLS.
